[57] **CLAIM**

The ornamental design for a baseball bat having a rattle-snake rattle end, as shown and described.

DESCRIPTION

FIG. 1 is a perspective view of a baseball bat having a rattlesnake rattle end showing my new design;

FIG. 2 is an elevational view thereof, all other sides being identical; and,

FIG. 3 is a left end view thereof.

The portion of the knob end of the bat not disclosed in the drawings forms no part of the claimed design.
